(57) **CLAIM**

The ornamental design for a portable toilet, as shown and described.

DESCRIPTION

FIG. 1 is a front, top and left side perspective view of a portable toilet, showing my new design;

FIG. 2 is a rear, bottom and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded view of the portable toilet, with the cover closed and separated from the main body; and,

FIG. 10 is an enlarged view of the selected portion 10 in FIG. 9.

The broken lines shown in the drawings depict portions of the portable toilet that form no part of the claimed design. The broken lines in FIGS. 9 and 10 showing a detail marker and encircling the enlargement form no part of the claim.
